ABSTRACT

An automatic scoring apparatus for a dart game utilizing a plurality of light detecting elements situated on the periphery of a dart board. These light detecting elements are aligned to receive light emitted by a plurality of light sources so that a dart embedded in the dart board will block the path of light from the light sources to the light detecting elements. A microprocessor and associated electronic circuitry continually scan the light detecting elements to detect a decrease in the amount of light incident on any particular light detecting elements indicative of the presence of a dart in the dart board. The location of the dart is calculated mathematically from the shadow location information.

APPARATUS AND METHOD FOR
AUTOMATICALLY SCORING A DART GAME

This invention relates to dart games, and more particularly, to the automatic calculation of the position of a dart embedded in a dart board to permit the dart game to be automatically scored as the darts are thrown.

BACKGROUND OF THE INVENTION

Numerous automatic scoring systems exist for dart games. For example, U.S. Pat. No. 3,836,148 for "Rotatable Dart Board, Magnetic Darts and Magnetic Scoring Switches" discloses an automatic scoring dart board apparatus utilizing magnetic darts. A rotatably mounted dart board rotates to bring the magnetic darts embedded in the dart board into alignment with a plurality of magnetic actuatable switches located behind the dart board. U.S. Pat. No. 3,790,173 for "Coin Operated Dart Game" discloses a dart game which automatically and electrically accumulates the score of a thrown dart. A special surface for the dart board is required to electrically register the position at which the dart strikes the target. U.S. Pat. No. 3,454,276 for "Self Scoring Dart Game" discloses impact actuated electrical switches which activate relays to total the score of the thrown darts. Other automatically scored dart games are disclosed in U.S. Pat. No. 2,523,773; in U.S. Pat. No. 2,506,475; and in U.S. Pat. No. 2,165,147. The automatically scoring dart games disclosed in the prior art utilize either special darts or a special dart board surface. The present invention, on the other hand, provides a fast and accurate automatic system to calculate the position of an ordinary dart embedded within an ordinary dart board. A special dart board and/or special darts are not needed.

SUMMARY OF THE INVENTION

The present invention overcomes the disadvantages inherent in the dart board systems disclosed in the prior art by providing an automatic dart board scoring system which requires neither a specially constructed dart board nor specially constructed darts. The dart board system of the present invention utilizes a plurality of light emitting elements and a plurality of light detecting elements situated on the periphery of a standard dart board. Each light source emits light across the surface of the dart board in a manner that enables a number of the light detecting elements on the opposite side to respond to the emitted light. A dart embedded in the dart board will block the path of the light from two or more of the light sources to the associated light detecting elements. A microprocessor and associated electronic circuitry continually scan the outputs of the light detecting elements in order to detect a decrease in the amount of light incident on any of the light detecting elements. A decrease in the amount of incident light is indicative of the presence of a dart in the dart board.

After detecting the presence of a dart, the system mathematically determines the position of the embedded dart, using the observed positions of those light detecting elements in the shadow of the dart and the known positions of the associated light sources. After the position of the dart is calculated, the system computes the points scored by that dart, and updates the game score. The system detects additional darts by detecting a difference in the results of a new scan of the outputs of the light detecting elements from the results

from the prior scan that are stored in memory. The position of the new dart is then mathematically determined in the same manner as before, and the game score is updated accordingly.

An object of the present invention is to provide means for automatically scoring a dart game. A further object of the invention is to provide means for automatically calculating the position of a dart embedded in a dart board. Yet another object of the invention is to provide an automatic dart board scoring system which utilizes an ordinary dart board and ordinary darts. Still another object of the invention is to provide means for automatically calibrating the process of determining the dart position, so that the need for maintenance of the system is minimized. A further object of the invention is to provide means for automatically calculating the positions of a plurality of darts sequentially thrown and simultaneously embedded in a dart board.

Other objects of the invention will become readily apparent from the following detailed description and the drawings herein.

BRIEF DESCRIPTION OF THE DRAWINGS

FIG. 1 is a perspective view of the automatic scoring apparatus of the invention showing the placement of a dart board within said apparatus.

FIG. 2 is a schematic view of the dart board showing the location of two calibration points and the scoring value of various sectors of said dart board.

FIG. 3 is a schematic view of the dart board showing the relative position of two arrays of light detecting elements and two light sources used to detect the location of darts embedded in the dart board.

FIG. 4 is a schematic view of the blockage of light from two light sources to two arrays of light detecting elements by a dart embedded in the dart board.

FIG. 5 is a schematic view showing the distances from the two calibration points of the dart board to the two light sources and showing the relative position of the two calibration points with respect to the two light sources.

FIG. 6 is a schematic view of a set of triangles representing the distances shown in FIG. 5 showing certain angles and distances which must be calculated in order to calibrate the exact position of the dart board when the dart board is initially positioned within the automatic scoring apparatus.

FIG. 7 is a schematic view showing the dart board circle divided into four sectors and showing the line from which an angular coordinate for locating the position of a dart is measured.

FIG. 8 is a schematic view of a set of triangles representing the distances from the two light sources to a dart embedded in the third sector of the dart board showing certain angles and distances which must be calculated in order to determine the exact position of said dart embedded in the dart board.

FIG. 9 is a schematic view of a set of triangles representing the distances from the two light sources to a dart embedded in the first sector of the dart board showing certain angles and distances which must be calculated in order to determine the exact position of said dart embedded in the dart board.

FIG. 10 is a block diagram illustrating the interconnection of various electronic circuits of the apparatus.

FIG. 11 is a circuit diagram showing a representation of a field effect transistor switch having decoding cir-

cuitry for decoding binary signals on input lines to individually activate one of eight phototransistors.

FIG. 12 is a circuit diagram showing the interconnection of various binary counters and decoders for sequentially selecting and activating light detecting elements such as phototransistors.

FIG. 13 is a circuit diagram showing the connection of the output of a series of field effect transistor switches to a comparitor circuit.

FIG. 14 is a circuit diagram symbolically showing the connection of a single phototransistor to a comparitor circuit.

FIG. 15 is a schematic view of the dart board, varying the design shown in FIG. 3 by addition of a third light source and a third array of light detecting elements.

FIG. 16 is a schematic view of the dart board in an alternative embodiment of the invention, showing the placement of light sources and arrays of light detecting elements on all four sides of the dart board.

FIG. 17 is a schematic view of the angles and distances used in an alternative embodiment of the invention to compute the exact position of an embedded dart.

DESCRIPTION OF THE PREFERRED EMBODIMENT

The automatic scoring apparatus of the present invention will be denoted generally by the numeral 20. As shown in FIG. 1 automatic scoring apparatus 20 may be contained within an automatic scoring apparatus housing 22 supported by an automatic scoring apparatus base 24. As shown in FIG. 1, one wall of said housing 22 possesses a circular aperture 26 having dimensions slightly larger than the dimensions of a regulation size dart board. A regulation size dart board 28 may be mounted within said housing 22 through said circular aperture 26 and inset inwardly from the inner surface of the associated wall to define a space therebetween. After dart board 28 has been mounted within housing 22, one or more darts 30 may be thrown at dart board 28 during the course of a dart game. FIG. 1 illustrates a dart 30 embedded in dart board 28.

FIG. 1 also illustrates in dotted outline the placement of a first light source 32 and a second light source 34 within housing 22 on opposite sides of dart board 28. First light source 32 is placed within housing 22 so that light from first light source 32 will illuminate a space immediately above and adjacent to the surface of dart board 28. The light from first light source 32 passes through illuminated space and over the surface of dart board 28 in a generally horizontal direction. The light from first light source 32 is then incident upon a first array of light detecting elements 36 such as photoelectric cells mounted within housing 22 on one side of dart board 28. Said first array of light detecting elements 36 is arranged in a circular arc with respect to first light source 32. That is, the distance from first light source 32 to each of the light detecting elements in said first array of light detecting elements 36 is the same. Thus, the light detecting elements in said first array of light detecting elements 36 define a circular arc. The relative position of said first array of light detecting elements 36 within housing 22 is shown in dotted outline in FIG. 1.

Similarly, second light source 34 is located within housing 22 on one side of dart board 28 so that second light source 34 may horizontally illuminate the space immediately above and adjacent to dart board 28 from a second direction. Light from second light source 34 is

incident upon a second array of light detecting elements 38 positioned on the side of dart board 28 opposite second light source 34. Said second array of light detecting elements 38 is arranged in a circular arc with respect to second light source 34 in a manner identical to that described for the first array of light detecting elements 36. The relative position of the second array of light detecting elements 38 within housing 22 is shown in dotted outline in FIG. 1.

The construction and operation of first light source 32 and first array of light detecting elements 36 is identical to the construction and operation of second light source 34 and second array of light detecting elements 38. The light sources, 32 and 34, and the arrays of light detecting elements, 36 and 38, define a system for generating and receiving light which is symmetrical with respect to a straight line passing from the bottom of dart board 28 to the top of dart board 28. FIGS. 3 and 5 illustrate the symmetry of the light generating and receiving system.

When a dart 30 is thrown into dart board 28, then dart 30 embeds itself within dart board 28. As shown schematically in FIG. 4, the presence of dart 30 embedded within dart board 28 interrupts the light passing from first light source 32 to first array of light detecting elements 36 thereby casting a first shadow 40 on the first array of light detecting elements 36. Said dart 30 simultaneously interrupts the light passing from second light source 34 to second array of light detecting elements 38 thereby casting a second shadow 42 on the second array of light detecting elements 38.

The light detecting elements in the first array of light detecting elements 36 and in the second array of light detecting elements 38 may be photoelectric cells such as phototransistors or the like. As is well known, a phototransistor will cause a small amount of current to flow in the circuit in which it is connected when light is incident on said phototransistor. The presence of dart 30 embedded within dart board 28 may be detected when the shadows created by dart 30 fall upon and eclipse some of the phototransistors of the first array of light detecting elements 36 and eclipse some of the phototransistors of the second array of light detecting elements 38. The ambient light incident on the eclipsed phototransistors will be less than that light which the phototransistors would otherwise have received directly from an oppositely located light source. Therefore the current that the eclipsed phototransistors generate is less than the current generated by the phototransistors that are located immediately adjacent to the eclipsed phototransistors.

In one embodiment of the apparatus, two hundred fifty-six (256) phototransistors are positioned within said first array of light detecting elements 36 and two hundred fifty-six (256) phototransistors are positioned within said second array of light detecting elements 38. The individual phototransistors in arrays 36 and 38 are spaced at a distance of one tenth of an inch (0.10") inch from each other. The close spacing of the individual phototransistors with respect to the dimensions of a regulation size dart board (a circle with a diameter of approximately eighteen inches) causes a dart 30 to cast a shadow that will eclipse approximately three to five phototransistors. As will be more fully described below, the apparatus of the present invention comprises a microprocessor 4 having the capacity to detect the location of each of the eclipsed phototransistors and to store in its memory the identity of each of the eclipsed photo-

transistors. Microprocessor 44 also has the capacity to calculate the location of the center of a shadow that eclipses a group of phototransistors thereby establishing an accurate figure for calculating the position of dart 30.

The microprocessor 44 mathematically creates a model of the scoring areas of dart board 28 and correlates the actual position of dart board 28 with the mathematical model. In order that there be an exact correspondence between the actual dart board 28 and the mathematical model of the dart board residing in microprocessor 44 it is necessary for microprocessor 44 to have information giving it the exact location of dart board 28. Accordingly, whenever a new dart board 28 is placed within housing 22, it is necessary to calibrate the apparatus as described below.

A pin (not shown) fixedly mounted within housing 22 is formed to fit within a complementarily shaped recess (not shown) within the rear surface of dart board 28. When dart board 28 is mounted within housing 22 said pin fits within said recess to guide dart board 28 to a centered position within circular aperture 26 of housing 22. The fit between said pin and its complementarily shaped recess is tight enough to insure that dart board 28 will be located in the desired position to within a tolerance of plus or minus one fourth of an inch ($\frac{1}{4}$ ").

Next, a first calibration pin 50 is pushed into the exact center of the dart board 28. The location of first calibration pin 50 in dart board 28 will be denoted by the letter A as shown in FIG. 2. Then a second calibration pin 52 is pushed into dart board 28 at the bottom edge of dart board 28. The location of second calibration pin 52 is denoted by the letter B as shown in FIG. 2.

Turning now to FIG. 3, one can see that the light illuminating first array of light detecting elements 36 from first light source 32 is interrupted by both first calibration pin 50 and by second calibration pin 52. Second calibration pin 52 causes a shadow to be thrown upon first array of light detecting elements 36 at location D1. First calibration pin 50 causes a shadow to be thrown on first array of light detection elements 36 at location D2.

Similarly, the light illuminating second array of light detecting elements 38 from second light source 34 is interrupted by both first calibration pin 50 and by second calibration pin 52. First calibration pin 50 causes a shadow to be thrown on second array of light detecting elements 38 at location D3. Second calibration pin 52 causes a shadow to be thrown on second array of light detecting elements 38 at location D4.

The locations D1, D2, D3 and D4 may be used to calculate the numerical value of the angles α' and β' shown in FIG. 3. Angle α' is the angle between a line extending from second light source 34 through the center of the dart board 28 and a line extending from second light source 34 through the bottommost point of dart board 28. Angle β' is the angle between a line extending from first light source 32 through the center of dart board 28 and a line extending from first light source 32 through the bottommost point of dart board 28. The distance from first light source 32 to second light source 34 is a fixed constant and in this particular embodiment of the invention is exactly equal to thirty inches (30.00"). The radius of curvature of the first array of light detecting elements 36 is also a fixed constant and in this particular embodiment of the invention is equal to twenty-seven and one-fourth inches (27.25"). The radius of curvature of the second array of light detecting elements is also a fixed constant and is equal to

the radius of curvature of the first array of light detecting elements which in this particular embodiment of the invention is equal to twenty-seven and one-fourth inches (27.25").

Angle α' may be calculated in radians by dividing the arcuate distance from point D3 to point D4 by 27.25 inches. Because the light detecting elements are located 0.10 inches apart, the distance from D3 to D4 is equal to the number of light detecting elements between point D3 and point D4 times 0.10 inches. Therefore, angle α' can be determined by making the calculation:

$$\alpha'(\text{radians}) = \frac{(D4 - D3)(0.10)}{(27.25)} \quad (1)$$

15

Similarly, angle β' can be determined by making the calculation:

$$\beta'(\text{radians}) = \frac{(D2 - D1)(0.10)}{(27.25)} \quad (2)$$

FIG. 5 is a schematic view showing the distances from the two light sources, 32, and 34, to the two calibration pins, 50 and 52, located at points A and B, respectively. As shown in FIGS. 5 and 6, the letter E denotes the location of first light source 32 and the letter D denotes the location of second light source 34. The letter C denotes the point of intersection of a line drawn through points A and B with a line drawn through points D and E. Let the letter b denote the distance from point E to point C and let the letter d denote the distance from point C to point D. Similarly, let the letter a denote the distance from point E to point A and let the letter c denote the distance from point A to point D.

In this embodiment of the invention the distance between first calibration pin 50 (point A) and second calibration pin 52 (point B) is six and five eighths inches (6.625"). This distance is noted in FIG. 6. The letter h denotes the distance between point B and point C. As shown in FIG. 6, the letter x denotes the distance between point E and point B and the letter z denotes the distance between point B and point D.

The object of the calibration procedure is to provide microprocessor 44 with information for locating the center of dart board 28 to within the desired tolerance. At the beginning of the calibration procedure, microprocessor 44 knows the location of point E and point D. Microprocessor 44 also knows that point A is 6.625 inches away from point B. Microprocessor 44 also knows that the sum of the distances d and b equals 30.00 inches. The unknowns to be determined are the distances h and b. After microprocessor 44 knows the distances h and b, then microprocessor 44 has information exactly locating the center of dart board 28 (point A). With the center of dart board 28 located, microprocessor 44 can cause its mathematical model to exactly coincide with the physical dart board 28 mounted within housing 22, thereby permitting the darts 30 embedded within dart board 28 to be accurately located.

Turning now to the actual calculation of the values h and b, one sees that it is convenient to solve the problem by successive approximation. Microprocessor 44 first assumes that the distance represented by the letter x (the distance from point E to point B) is exactly fifteen inches (15.00"). From the law of sines:

$$\frac{\sin\gamma'}{x} = \frac{\sin\beta'}{6.625} \quad (3)$$

$$\sin\gamma' = \frac{x\sin\beta'}{6.625}$$

$$\gamma' = \sin^{-1} \frac{x\sin\beta'}{6.625} \text{ (radians)}$$

but the angle β' is known from Equation (2) and x has been assumed to be 15.00 inches. Therefore, the angle γ' can be calculated from Equation (3).

Once the angle γ' is known, then the distance represented by the letter a (the distance from point E to point A) can be calculated from the law of sines as follows:

$$\frac{\sin(180^\circ - \beta' - \gamma')}{a} = \frac{\sin\beta'}{6.625} \quad (4)$$

$$[6.625] [\sin(180^\circ - \beta' - \gamma')] = a\sin\beta' \quad 20$$

$$a = \frac{[6.625] [\sin(180^\circ - \beta' - \gamma')]}{\sin\beta'} \quad 25$$

Because the angle β' and γ' are known from Equations (2) and (3), the value of a may be calculated from Equation (4).

Now the values b and h are calculated:

$$b = a\sin\gamma' \quad 30 \quad (5)$$

$$h = \sqrt{x^2 - b^2} \quad 35 \quad (6)$$

These values of b and h are the values obtained by assuming that the distance x was equal to 15.00 inches. Using these values of b and h , one then calculates the distances represented by the letters d , z and c :

$$d = 30.00 - b \quad 40 \quad (7)$$

$$z = \sqrt{h^2 + d^2} \quad 45 \quad (8)$$

$$c = \sqrt{(h + 6.625)^2 + d^2} \quad 50 \quad (9)$$

These values of d , z and c are then used to calculate an approximated value for angle α' which shall be denoted as α'' . The value of the approximated angle α'' may be derived from the law of cosines as follows:

$$\text{Let } s = \frac{1}{2}[c + z + 6.625] \quad 55 \quad (10)$$

$$\text{then } r = \sqrt{\frac{(s - c)(s - z)(s - 6.625)}{s}} \quad 60 \quad (11)$$

and then

$$\alpha'' = 2 \tan^{-1} [r/(s - 6.625)] \quad 65 \quad (12)$$

The value of approximately angle α'' is then compared to the value of α' obtained from the calibration measurement and from Equation (1). If the calculated value of α'' is less than α' , then the value for x was assumed too large. If the calculated value of α'' is greater than α' , then the value for x was assumed too small. If x was assumed too large, then its value is decreased by 0.05 inch and the series of calculations described above is performed again. Similarly, if x was

assumed too small, then its value is increased by 0.05 inch and the series of calculations described above is performed again.

As each value of α'' is recalculated it is compared with the empirically determined value of α' . When α'' and α' have values within one thousandth of a radian (0.001 radian) of each other, the successive approximation calculations performed by microprocessor 44 are terminated and the values of b and h that were last calculated are stored in microprocessor 44. The values of b and h calculated when the angles α'' and α' are within 0.001 radian of each other locate the center of dart board 28 to within a tolerance of approximately twenty-five thousandths of an inch (0.025").

The calibration process described above must be performed each time a new dart board 28 is mounted within housing 22. First calibration pin 50 and second calibration pin 52 are removed from dart board 28 after calibration process has been completed. At this point, microprocessor 44 by using the last calculated values of b and h can mathematically correlate a model of the scoring areas of a dart board with the actual dart board 28. In short, microprocessor 44 now "knows" the location of dart board 28 with respect to housing 22.

Microprocessor 44 can use this information to calculate the location of a dart 30 embedded anywhere in the surface of dart board 28. Dart 30 may be located by using polar coordinates. FIG. 7 shows a schematic representation of dart board 28 divided into four equal sectors by two perpendicular lines passing through the center of dart board 28. The four sectors correspond exactly to the four well-known quadrants in trigonometry. That is, first sector 54 corresponds to Quadrant I in trigonometry (0° to 90°), second sector 56 corresponds to Quadrant II (90° to 180°), third sector 58 corresponds to Quadrant III (180° to 270°), and fourth sector 60 corresponds to Quadrant IV (270° to 360°). The location of dart 30 in dart board 28 may be represented in polar coordinates by giving a radial coordinate (denoted by a') equal to the distance from the center of dart board 28 (point A) to the location of dart 30 within said dart board 28 and by giving an angular coordinate (denoted by ϕ) measuring the angle between said radius a' and the line between first sector 54 and fourth sector 60 as shown in FIG. 7.

FIGS. 8 and 9 illustrate the method of calculation used by microprocessor 44 to find the locating coordinates of the position of dart 30 in dart board 28. Turning first to FIG. 8, one sees that when the dart 30 is located in third sector 58 the dart is in the lower left hand portion of dart board 28. Let the location of the dart 30 in third sector 58 be denoted by the letter G and let the distance from point A to point G be denoted by the letter a' . As shown in FIG. 8, the radius a' is disposed at angle θ with respect to the boundary line between second sector 56 and third sector 58.

Let the distance between point E (the location of first light source 32) and point G be denoted by the letter a and let the distance between point D (the location of second light source 34) and point G be denoted by the letter c. The letters d, b and h have the meanings previously assigned to them in the description of the calibration process.

The electronic circuitry of the apparatus (which will be more fully described below) scans the first array of light detecting elements 36 and the second array of light detecting elements 38 to determine the location of the

first shadow 40 and the second shadow 42 on the arrays of the light detecting elements. The angles α and β shown in FIG. 8 are calculated from the location of said shadows on said arrays of light detecting elements in the same manner as previously described for the calibration process.

Specifically, the angle α in radians equals the arcuate distance along the arc from point E to the point of intersection of the second shadow 42 with the second array of light detecting elements 38 divided by the radius of arc, here 27.25 inches.

$$\alpha(\text{radians}) = \frac{(D5 - D6)(0.10)}{(27.25)} \quad (13)$$

where D5 equals the number of the light detecting element in the second array of light detecting elements 38 corresponding to the location of the second shadow 42 and where D6 equals the number of the light detecting element in the second array of light detecting elements 38 corresponding to the location of the first light source 32.

Similarly, the angle β in radians equals the arcuate distance along the arc from point D to the point of intersection of the first shadow 40 with the first array of light detecting elements 36 divided by the radius of arc, here 27.25 inches.

$$\beta(\text{radians}) = \frac{(D7 - D8)(0.10)}{(27.25)} \quad (14)$$

where D7 equals the number of the light detecting element in the first array of light detecting elements 36 corresponding to the location of the first shadow 40 and where D8 equals the number of the light detecting element in the first array of light detecting elements 36 corresponding to the location of the second light source 34.

After microprocessor 44 has calculated the values of the angles α and β as described above, the values of the unknown coordinates a' and θ are calculated as will now be described. First, the radial distance from point E to point G is calculated from the law of sines as follows:

$$\frac{\sin \alpha}{a} = \sin \frac{[180^\circ - (\alpha + \beta)]}{d + b} \quad (15)$$

$$a = \frac{(d + b)\sin \alpha}{\sin [180^\circ - (\alpha + \beta)]}$$

Because the values of α , β , d and b are known, the value of a may be found using Equation (15).

The values of the rectilinear coordinates of a (x and y) shown in FIG. 8 are then calculated using the calculated value of a .

$$x = a \sin \beta \quad (16)$$

$$y = a \cos \beta \quad (17)$$

Then, the values of the rectilinear coordinates of a' (x' and y') shown in FIG. 8 are calculated from the calculated values of x and y.

$$x' = x - b \quad (18)$$

$$y' = y - (6.625 + h) \quad (19)$$

The rectilinear coordinates x' and y' may then be transformed into polar coordinates using the equations:

$$a' = \sqrt{(x')^2 + (y')^2} \quad (20)$$

$$\text{and} \quad \theta = \sin^{-1}(|y'|/a') \quad (21)$$

where $|y'|$ is the absolute value of y' .

Note that in this example the value of y' is negative. This indicates that the dart 30 is located in either the third sector 58 or the fourth sector 60 of dart board 28. Also note that the conversion of the angle θ derived from Equation (21) to a corresponding angle ϕ as described and shown in FIG. 7 may be accomplished by adding 180° to the angle θ . This is because the angle θ lies in the third sector 58 of dart board 28.

The equations derived above for the example shown in FIG. 8 of a dart 30 embedded in the third sector 58 of dart board 28 have general applicability. For example, consider the additional case of a dart 30 embedded in the first sector 54 of dart board 28 as shown in FIG. 9. In this example, the location of dart 30 in the first sector 54 of dart board 28 is denoted by the letter G, the distance from point A to point G is denoted by the letter a' , and the radius a' is disposed at angle θ with respect to the boundary line between first sector 54 and fourth sector 60. The letters a, b, c, d and h have the meanings previously assigned to them in the earlier example.

As before, the angles α and β shown in FIG. 9 are calculated from the location of the shadows on the arrays of photodetectors in the same manner as in the previous example. Equation (15) is used to calculate the appropriate value of a' from the values of α and β . Inspection of FIG. 9 shows that Equations (16) and (17) give the correct value of the rectilinear coordinates of a (x and y) in terms of a and β .

Further inspection of FIG. 9 shows that Equations (18) and (19) give the correct value of the rectilinear coordinates of a' (x' and y'). In this case, however, the value of x' is negative which indicates that dart 30 is located in either the first sector 54 or the fourth sector 60 of dart board 28. In this example, the value of y' is positive because the dart is located in the first sector 54 of dart board 28. The values of a' and θ may be calculated from Equations (20) and (21) as before to give the exact locations of dart 30 in the first sector 54 of dart board 28.

The positive and negative values of the coordinates x' and y' permit the correlation of each angle θ with its corresponding angle ϕ . Specifically, if x' is negative and y' is positive, then the dart location is in the first sector 54 and ϕ equals θ . If x' is positive and y' is positive, then the dart location is in the second sector 56 and ϕ equals 180° minus θ . If x' is positive and y' is negative, then the dart location is in the third sector 58 and ϕ equals 180° plus θ . If x' is negative and y' is negative, then the dart location is in the fourth sector 60 and ϕ equals 360° minus θ .

The values of the angle ϕ and of the radius a' may be correlated to the scoring areas of dart board 28 shown in FIG. 2. With respect to the correlation of the angle ϕ , one may see that if the value of the angle ϕ that is greater than 9° but less than 27° then the dart is in the sector numbered 14 as shown in FIG. 2. A value of the angle ϕ that is greater than 27° but less than 45° indicates a dart in the sector numbered 9 and so forth.

around the dart board up to the value of ϕ equal to 351° . If the value of the angle ϕ is greater than 351° but less than 360° or is equal to or greater than 0° but less than 9° , then the dart is in the sector numbered 11 as shown in FIG. 2. The various angles of ϕ corresponding to the various numbered sectors of the dart board shown in FIG. 2 are summarized below:

If ϕ is greater than	but is less than	then dart is in sector
9°	27°	14
27°	45°	9
45°	63°	12
63°	81°	5
81°	99°	20
99°	117°	1
117°	135°	18
135°	153°	4
153°	171°	13
171°	189°	6
189°	207°	10
207°	225°	15
225°	243°	2
243°	261°	17
261°	279°	3
279°	297°	19
297°	315°	7
315°	333°	16
333°	351°	8
351°	9°	11

With respect to the correlation of the radius a' to the scoring areas of dart board 28, one sees that if the value of a' is less than one-fourth inch (0.250"), then the dart is inside the double bullseye. If the value of a' is greater than one-fourth inch (0.250") but less than five-eighths inch (0.625"), then the dart is inside the single bullseye. Similarly, a value of a' between three and three-quarters inches (3.750") and four and one-eighth inches (4.125") indicates that the dart is inside the triple ring and a value of a' between six and one-fourth inches (6.250") and six and five-eighths inches (6.625") indicates that the dart is inside the double ring. If a' is greater than six and five-eighths inches (6.625"), then the dart is not within the scoring areas of the dart board. The various values of a' corresponding to the various concentric rings of the dart board shown in FIG. 2 are summarized below.

If a' is greater than	but is less than	then dart is in
0.000 inch	0.250 inch	Double Bullseye
0.250 inch	0.625 inch	Single Bullseye
0.625 inch	3.750 inches	Single
3.750 inches	4.125 inches	Triple
4.125 inches	6.250 inches	Single
6.250 inches	6.625 inches	Double

For an example of how a score may be calculated, assume that ϕ has been found to be 250° and that a' has been found to be 3.86 inches. These values indicate that the dart is in numbered sector 17 within the triple ring. Therefore, the score of this particular dart would be calculated to be 3 times 17 or 51. As a second example, assume that ϕ has been found to be 65° and that a' has been found to be 5.2 inches. Then values indicate that the dart is in numbered sector 5 within a single ring. Therefore, the score of this particular dart would be calculated to be 5.

Of course, any system of scoring may be utilized in connection with the dart locating apparatus and method described herein. The underlying principles of the auto-

matic scoring system of the invention may be adapted to any particular set of values that may be chosen. In order to use a different set of scoring values and scoring areas with the apparatus one would only have to provide microprocessor 44 with a different set of parameters relating the values of a' and ϕ to the appropriate scoring values and scoring areas. The values a' and ϕ would be determined in the same manner as previously described.

Turning now to a description of the microprocessor and associated electronic circuitry used in conjunction with the apparatus previously described, one sees with reference to FIG. 10 that the electronic portion of the apparatus may be symbolically represented in block diagram form. Specifically, FIG. 10 illustrates the interconnection of the various elements of the apparatus including a microprocessor 44 (containing a central processing unit or CPU), random access memory 64 (RAM), read only memory 66 (ROM), an address bus 68, a data bus 70 and a control bus 72. A battery back-up 74 may be optionally provided for operation during power failures.

Other electronic circuitry may be used with the apparatus as indicated in FIG. 10. For example, a cathode ray tube 76 (CRT) may be utilized to display scoring information or instructions to the players during the course of a game. CRT 76 is depicted in FIG. 1 mounted within base 24. A transparent non-breakable cover 78 must be used to protect the front of CRT 76 from being penetrated by a carelessly thrown dart. Such a cover 78 is also depicted in FIG. 1. A video display controller 80 and associated video display circuits 82 as shown in FIG. 10 may be connected to the address bus 68, data bus 70 and control bus 72 for controlling the operation of CRT 76.

The visually transmitted information imparted by CRT 76 may be supplemented with audibly transmitted information from a speaker (not shown) within apparatus 20. Audio circuits 88 may be connected to the address bus 68, data bus 70 and control bus 72 as shown in FIG. 10 to transmit information from microprocessor 44, RAM 64 or ROM 66 to said speaker. The audio circuits 88 cause the computer formatted information to be translated into an audibly intelligible form for transmission to the speaker.

Microprocessor 44 may control several different types of electronic circuitry via control bus 72. For example, coin acceptor circuitry 92 for monitoring the operation of a coin acceptor 94 mounted within base 24 may be controlled by microprocessor 44. The particular types of electronic circuitry used in apparatus 20 may include coin acceptor circuitry 92, player control circuitry 96 for keeping track of which player is next to play, decoder circuitry 98, light source circuitry 102, and light detection circuitry 103 for detecting the presence and location of a dart 30.

Turning now to a description of the decoder circuitry 98, light source circuitry 102, and light detection circuitry 103, one notes that the first array of light detecting elements 36 is mounted on a first detector board (not shown) and the second array of light detecting elements 38 is mounted on a second detector board (not shown). In this embodiment of the invention each detector board contains two hundred fifty-six (256) light detecting elements which may be phototransistors 104. The phototransistors 104 may be any of a number of well known types, including the germanium type or the silicon type or gallium-arsenide type. The phototransis-

tors 104 used in the preferred embodiment of the invention are the n-p-n silicon type, specifically type LS600.

Associated with each phototransistor 104 is a field effect transistor switch. Any of a number of types of field effect transistor switches may be used in this particular application. In the preferred embodiment of the invention, however, an AM3705 switch set 106 containing selective decoding circuitry is used.

As shown in FIG. 11, said switch set 106 possesses a chip-enable input CE and three binary input lines A, B, and C. The switch set 106 is connected to eight (8) phototransistors 104. The switch set 106 contains a three line to eight line decoder for turning on each of the eight phototransistors 104 individually. Specifically, when a signal is received on the chip-enable CE line 108 the switch set 106 is receptive to a binary input on lines A, B, and C. The decoder in the switch set 106 reads the binary input from lines A, B, and C and decodes it to indicate which of the eight phototransistors 104 is to be activated.

Because there are two hundred fifty-six (256) phototransistors 104 on each detector board and because an individual switch set 106 is connected to and capable of reading eight phototransistors, there are thirty-two switch sets 106 on each detector board. The dotted line around the switch set 106 depicted in FIG. 11 indicates that it is only one of thirty-two such switch sets connected in parallel. That is, while each switch set 106 has its own switch set chip enable input line 108 and its own switch set output line 110, each switch set 106 has input from lines A, B, and C.

The decoder circuitry 98 of the present invention is designed to select one of said thirty-two switch sets 106 according to instructions received from the microprocessor 44. The decoder circuitry 98 also provides the binary input signals to lines A, B, and C of each switch set 106 for finding a particular phototransistor 104.

As shown in FIG. 12, the decoder circuitry 98 comprises binary counters and decoders. Prior to scanning the detector boards the microprocessor 44 sends out a signal on the line SET Z. A high signal on the line SET Z from the microprocessor 44 zeros the two four bit binary counters, 112 and 114 shown in FIG. 12. The binary counters 112 and 114 are reset to zero after each scan in order to assure that phototransistor number 0 is the first one read at the beginning of each scan.

As shown in FIG. 12, the output from ports Ao, Bo and Co from four bit binary counter 112 are fed to lines A, B, and C of each of the thirty-two switch sets 106. As the count from the four bit binary counter 112 increases from 0 to 7, the lines A, B, and C carry signals representative of the binary values 0 through 7 to each of the thirty-two switch sets 106. Only one of the thirty-two switch sets, however, is functional at any one time. It is that switch set which has its chip-enable turned on by the decoder as will be more fully described below.

Turning now to a description of the decoder, one sees that it comprises one two line to four line decoder 116, and four three line to eight line decoders 118, 120, 122 and 124. Decoder 116 is used to enable one of the four three line to eight line decoders at a time. Specifically, either decoder 118, 120, 122 or 124 will be enabled at any one time. The chip-enable line for each of the three line to eight line decoders is line fourteen as shown in FIG. 12. The remaining three input lines to each of the four three line to eight line decoders are connected to a common source. Thus, each of the three line to eight

line decoders receives the same count information over the input lines labeled 1, 2, and 3 but only that particular three line to eight line decoder which has been selected by a high signal on its chip-enable line from the two line to four line decoder 116 may receive the set information.

By way of illustrative example, consider three line to eight line decoder 118 which is designed to scan or monitor the first sixty-four phototransistors 104 numbered from 0 to 63. At the beginning of the scanning process, a high signal was transmitted over line SET Z to zero the four bit binary counters 112 and 114. At that point, the output from binary counter 114 at ports A₁, B₁, C₁ and D₁ was 0. Zero inputs on lines two and three of two line to four line decoder 116 causes the output of line 4 to be high while the outputs of the remaining lines 5 through 7 are zero. The high signal on line 4 of decoder 116 enables three line to eight line decoder 118. Also at this time the input to three line to eight line decoder 118 on lines 1, 2 and 3 are all 0. This selects the first of the thirty-two switch sets 106 for reading the phototransistors 0 through 7.

Specifically, the output from three line to eight line decoder 118 on lines 4 through 7 and lines 9 through 12 is as follows. Line 4 is high and lines 5 through 7 and lines 9 through 12 are 0. Line 4 of eight line to three line decoder 118 leads to the chip-enable input line 108 of the first of the thirty-two switch sets 106. The remaining lines 5 through 7 and lines 9 through 12 of the three line to eight line decoder 118 lead to the chip-enable inputs of the next seven switch sets 106 in sequential order. Thus, three line to eight line decoder 118 enables only one of each of the first eight switch sets 106, numbers 0 through 7 at a time.

To return to our example, at this point the inputs we have described have enabled the light detection circuitry 103 to detect the output of phototransistor number 0. After an appropriate amount of time has elapsed for data line settling, microprocessor 44 reads the detector output line 126 (described more fully below) and then sends out a clock pulse on clock line 14 of four bit binary counter 112 to switch the scanner to read the next phototransistor 104, in this case phototransistor number 1. The pulse on the clock line 14 causes four bit binary counter 112 to change from a binary 0 count to a binary 1 count, corresponding in this case to phototransistor number 1. This process is repeated for each phototransistor up through phototransistor number 7. The process of monitoring a phototransistor 104 occurs eight times for each switch set 106.

After phototransistor number 7 has been sampled, the next clock pulse causes the output on line 11 leading from port Do of four bit binary counter 112 to go high. At this point, three line to eight line decoder 118 is still selected. However, the input to decoder 118 now has a high signal on line 1. This causes output line 4 which was formerly high to go low and also causes output line 5 which was formerly low to go high. This combination causes the second switch set 106 for phototransistors 8 through 15 to be enabled. The process previously described for sampling the eight phototransistors 104 of a switch set 106 is repeated.

During the sampling of the eight phototransistors 104 of a particular switch set 106 the count on lines A, B, and C increments from 0 to 7 sequentially selecting each phototransistor 104 for sampling as previously described. In a similar manner, inputs on lines 1, 2 and 3 to three line to eight line decoder 118 are similarly incre-

mented from 0 to 7 to sequentially enable switch sets numbers 0 through 7.

Once all the switch sets 106 under the control of decoder 118 have been sampled, the output from port C1 of four bit binary counter 114 goes high thereby causing decoder 116 to select decoder 120 by placing a high signal on output line 5 of decoder 116 thereby enabling decoder 120. Simultaneously, the output on line 4 from decoder 116 goes low, thereby turning off decoder 118.

All switch set outputs on a side are connected together to a common collector resistor 128 as shown in FIG. 13. Common collector resistor 128 is connected to the plus input side of a comparator 130 as shown in FIG. 13. As previously described, only one individual phototransistor 104 is sampled at a time. FIG. 14 schematically represents a circuit in which a single phototransistor 104 may be switched into series connection with comparator 130. Switch 132 symbolically represents an appropriate switch set 106. If at the time a phototransistor 104 is sampled, it is covered by a shadow, then its output will be high and a high level signal will be delivered to the plus input of the comparator 130. If at the time the phototransistor 104 is sampled it is not covered by a shadow, then its output signal will be low and a low level signal will be delivered to the plus input of the comparator 130.

The minus input of the comparator 130 as shown in FIGS. 13 and 14 is connected to a variable resistor 134. The voltage delivered to the minus input of comparator 130 by variable resistor 134 is adjusted by varying the resistance of variable resistor 134. The value of this voltage is chosen to provide a voltage level to the minus input of comparator 130 that will allow reliable detection of both high gain and low gain phototransistors.

The output of comparator 130 will be high in shadow conditions and low in non-shadow conditions. A high or low signal is indicative, respectively, of the presence or absence of a shadow on a particular phototransistor 104. The microprocessor 44 reads the signal on the detector output line 126 coming from comparator 130 and stores in its memory the number of the particular phototransistor 104 if the signal on the detect line indicates that a shadow was present on the phototransistor.

The foregoing description of the scanning and detection process has been directed to the operation of a single detector board. It has been discovered, however, that the light source circuitry 102, light detection circuitry 103, and microprocessor 44 can be adapted to monitor the outputs of both detector boards quickly enough so that the scanning of both detector boards may be done effectively simultaneously. The time required for the electronic circuitry 102 and 103, and microprocessor 44 to complete one complete scan is less than one second. Thus, during the course of a dart game the electronic circuitry 102 and 103 makes many scans looking for a dart 30 embedded in the dart board 28. When the scanner and detector electronic circuitry 102 and 103 indicates the presence of a dart 30 embedded in the dart board 28, the microprocessor 44 calculates the location of the dart 30 in the dart board 28 as previously described.

When more than one dart 30 is embedded in dart board 28 at the same time, the existence of multiple overlapping shadows may make it difficult to calculate the positions of the darts. This difficulty may be overcome by using a third light source 136 in conjunction with a third array of light detecting elements 138. FIG.

15 illustrates how the third light source 136 and the third array of light detecting elements 138 may be situated with respect to the first light source 32, the second light source 34, the first array of light detecting elements 36, the second array of light detecting elements 38 and the dart board 28.

In operation, first light source 32 and second light source 34 are turned on and the locations of the shadows of the darts 30 on the first array of light detecting elements 36 and on the second array of light detecting elements 38 are determined and stored in the memory of microprocessor 44 as previously described. Then second light source 34 and third light source 136 are turned on and the locations of the shadows of the darts 30 on the second array of light detecting elements 38 and on the third array of light detecting elements 138 are similarly determined and stored. Finally, first light source 32 and third light source 136 are turned on, and the locations of the shadows on the first array of light detecting elements 36 and on the third array of light detecting elements 138 are determined. The principle of operation for each of the three sets of two light sources is the same as that previously described for first light source 32 and second light source 34.

The present invention may also be embodied in alternate geometrical forms. For example, an alternate embodiment of the invention is shown in FIG. 16. While this embodiment of the invention is substantially similar in design and operation to the apparatus 20 shown in FIG. 1, the alternate embodiment uses a different physical configuration of light emitting and detecting elements, and therefore a different mathematical technique, to determine the position of an embedded dart.

FIG. 16 shows the physical configuration of the light sources 140 through 166 and their associated arrays of light detecting elements 168 through 194, both of which are situated along the four sides of the dart board 28, forming a square around the board. The distance between each phototransistor 104 within each array 168 through 194 is one tenth of one inch (0.10"). Sixty-four phototransistors 104 are in each array 168 through 194, with the exception of arrays 174, 180, 188 and 194 which contain only thirty-two phototransistors 104. Each light source 140 through 166 is associated to one and only one array of light detecting elements 168 through 194, so that the outputs of a given array 168 through 194 will correlate to the shadows blocking light from one and only one light source 140 through 166. For example, the outputs from the phototransistors 104 in array 168 will represent the presence or absence of light from light source 140 only.

The block diagram of FIG. 10 is equally applicable to this embodiment of the invention. After the microprocessor 44 has received inputs from the coin acceptor circuitry 92 and the player control circuitry 96 indicating that a game has begun, the microprocessor 44 then sequences the light sources 140 through 166 and associated arrays of light detecting elements 168 through 194 to look for a dart 30 embedded in the dart board 28. The sequence and data gathering routines are initiated by the microprocessor 44, and carried out through the decoder circuitry 98. The sequence begins by enabling the first light source 140 and disabling all others, so that only light source 140 emits light across the dart board 28. This light is received by its associated array of light detecting elements 168. During the time that light source 140 is emitting light, the microprocessor 44 via the decoder circuitry 98, sequentially enables the output

from each phototransistor 104 in array 168 using a method functionally similar to that previously described in connection with the first embodiment of the invention. This embodiment uses decoder circuitry 98 and switch sets 106 functionally similar to, but organized differently from, the first embodiment of the invention because, at the most, only 64 phototransistors 104 are sequenced in each array, rather than 256 as in the first embodiment of the invention. The actual decoders used here to enable the individual phototransistor outputs are HEF4067B sixteen-to-one decoders. The outputs of the phototransistors 104 are serially received and stored in RAM 64 by the microprocessor 44 in the order that the phototransistors 104 are enabled, by a method functionally similar to the comparator technique of the first embodiment.

This process of enabling the light sources 140 through 166, during which the associated light detecting element arrays 168 through 194 are sequentially accessed and the output state fed back to the microprocessor 44, is repeated for each of the remaining light sources 142 through 166, in sequence. The phototransistors 104 in each array 168 through 194 are accessed only during the time its associated light source 140 through 166 is emitting light; each array 168 through 194 is 25 associated with one and only one light source 140 through 166.

The microprocessor 44 detects the presence of an embedded dart 30 by comparing the results from the most recent sequence of enabling the light sources 140 through 166 and associated phototransistors 104 with those results from the next most recent sequence. Both sets of results are stored and retained in random access memory RAM 64. The results of the initial sequence, before the first dart 30 is thrown, represent the presence 35 of light sensed by all phototransistors 104. As it performs this sequence, the microprocessor 44 treats light sources 140 through 152 (and the associated light detecting element arrays 168 through 180) as one "channel" and groups the remaining light sources 154 40 through 166 (and the associated light detecting arrays 182 through 194) into the second "channel". Note that the two channels represent light patterns perpendicular to one another. Because the arrays of light detecting elements 168 through 194 each are dedicated to one and 45 only one light source so that each physical location on the dart board corresponds to one and only one light pattern from each channel, one and only one light detecting element array from each of the two channels will detect the absence of light due to the shadow of an embedded dart 30. The microprocessor 44 detects the presence of the first embedded dart 30 by detecting a difference in the results of the first scan after the dart 30 is embedded, from the initial scan with no dart present. The difference comes from one or more phototransistors 104 in one and only one array 168 through 194 in 55 each of the two defined channels. If multiple phototransistors 104 in one array show the absence of light, these phototransistors 104 must be in sequence (i.e., one continuous shadow) or else the microprocessor 44 will 60 perform an error routine and stop the game.

When an embedded dart 30 is detected by the microprocessor 44 as shown in FIG. 10, the microprocessor 44 begins the program routine which defines the position of the dart 30 in rectangular x-y coordinates. This routine begins by determining which of the light detecting element arrays 168 through 194, in this case 172 and 192, one from each of the two channels, detected the

absence of light. For each of these two arrays 172 and 192, the routine next determines the length of the shadow, measured by the number of adjacent phototransistors 104 in each array 172 and 192 which detected the absence of light. Once this is determined, the routine finds the midpoint of the "shadow" by subtracting one from the number of phototransistors 104 detecting the absence of light, dividing this number by two (ignoring any remainder), and adding the resultant number to the numerical position representing the first phototransistor 104 detecting the absence of light from the shadow.

The program routine then calculates the position of the embedded dart 30 using the trigonometric relationships displayed in FIG. 17, and considering the dart board area as an x-y grid with origin O at the bullseye. The positions of the shadow midpoints M_1 and M_2 are known. The positions of the associated light sources S_1 and S_2 are known. The first step calculates angles A_1 and A_2 from the perpendicular using the shadow midpoint positions M_1 and M_2 relative to the light source positions S_1 and S_2 , and the following relationships:

$$A_1 = \tan^{-1} \frac{(0.10)(M_{1x} - S_{1y})}{24.0} \quad (22)$$

and

$$A_2 = \tan^{-1} \frac{(0.10)(M_{1x} - S_{2y})}{24.0} \quad (23)$$

where point M_n has x-y components (M_{nx}, M_{ny}) , where point S_n has x-y components (S_{nx}, S_{ny}) , where 0.10 is the distance in inches between the centers of phototransistors 104, and where 24.0 is the distance in inches between the lines of phototransistors 104 on opposite sides of the dart board 28. Next, the routine computes the distance between S_1 and S_2 (denoted by the letter "c"), and also the angles L_1 and L_2 as follows:

$$c = \sqrt{(S_{2y} - S_{1y})^2 + (S_{2x} - S_{1x})^2} \quad (24)$$

$$L_1 = \tan^{-1} \frac{(S_{2y} - S_{1y})}{(S_{2x} - S_{1x})} \quad (25)$$

$$L_2 = 90^\circ - L_1 \quad (26)$$

The angles B_1 and B_2 are found, using previously calculated angles L_1 , L_2 , A_1 , and A_2 , and using the theorem which states that opposing angles created by a straight line intersecting two parallel lines are equal, as follows:

$$B_1 = L_2 + A_1 \quad (27)$$

$$B_2 = L_1 + A_2 \quad (28)$$

Note that A_1 and A_2 are signed angles, depending on their directions. In FIG. 17, A_1 is a negative angle. The triangle defined by the points S_1 , S_2 and D (dart position) is then used to calculate the distance between S_1 and D (denoted by the letter "a") using the law of sines:

$$a = \frac{c[\sin(180^\circ - (B_1 + B_2))]}{\sin B_2} \quad (29)$$

The displacements a_x and a_y , relative to S_1 , are then calculated as follows:

$$a_x = a \sin A_1 \quad (30)$$

$$a_y = a \cos A_2 \quad (31)$$

These displacements are signed as required. The displacements a_x and a_y are then adjusted to represent the position of the dart 30 from the origin O (i.e., the bullseye of the dart board 28) as follows:

$$x = a_x - S_{1x} \quad (32)$$

$$y = a_y - S_{1y} \quad (33)$$

The x-y coordinates of the dart position may be adjusted automatically using calibration constants in a manner similar to that previously described. The calibration technique used in this embodiment of the invention requires the player to place a dart 30 in the bullseye (and mathematical origin) of the dart board 28 at the time that the apparatus 20 is initially powered up. The microprocessor 44 automatically begins the calibration routine and determines the position of the dart 30 in the same manner as previously described. After the dart's position has been calculated, the values of the x-y displacements are stored in RAM 64. The x-y calibration displacements are subtracted from the calculated x-y coordinates of the thrown dart 30, so that the resultant x-y coordinates accurately correlate with the actual position of the dart board 28 within the apparatus 20.

After the microprocessor 44 has adjusted the x-y coordinates of the first embedded dart 30, the remaining routines compute the score value attributed to this dart. Using well-known trigonometric techniques, the rectangular x-y coordinates are converted into polar coordinates, namely, a radial distance and an angular displacement. These polar coordinates are then converted into a point value, with a multiplier for single, double, or triple values, in the same manner as previously described. The game score is then automatically updated.

After the score for the first dart 30 has been calculated and the game score updated, the microprocessor 44 begins to sequence the light sources 140 through 166 and light detecting element arrays 168 through 194 in the same manner as used in looking for the first dart, but now compares the results from each new sequence with the results stored in RAM 64 that denote the presence and position of the first dart 30. Any additional phototransistors 104 showing the absence of light in a new sequence, where that phototransistor showed the pres-

ence of light after the first dart 30 was embedded, will signal the microprocessor 44 to begin the position calculation routine again, after it analyzes the data to insure that no more than one continuous new shadow per channel has been detected. The position and score for this additional dart is computed in the same manner as the position and score of the first dart 30.

Special routines are used in this embodiment to preclude certain errors which are possible during a dart game. One such routine sequences the light source/detection sequence a second time, immediately after a dart has been detected. This prevents the microprocessor 44 from scoring the dart until two identical data patterns have occurred, thereby removing the possibility of error due to the vibration of the dart that occurs after the dart is embedded in the dart board. A second routine will properly adjust the game score if a shadow disappears, as it would if a dart fell out or was removed from the dart board, preventing the microprocessor 44 from executing an endless loop of software instructions. Also, the position-determining routine itself retains the angles and positions of previously thrown darts and uses them to compute the position of a new dart when the dart falls within a pre-existing shadow. The routine recognizes this event by detecting a new shadow on only one of the two channels and compensates by presuming that if only one new shadow exists, then the dart has fallen into the most recent dart's shadow for the unchanged shadow. The position-determining routine is also designed to detect and position a third dart in the rare event that its shadow is cast in such a way that the shadows from two prior darts appear to merge into a single shadow. The position routine, by looking only at changes in the data by operating sequentially on each dart after it is thrown, and by using only the positions of those phototransistors 104 which show a change in data, will treat the "single" shadow made by the three darts in sequence as three distinct shadows.

The assembly language program used by microprocessor 44 in the alternative embodiment is set forth below. The microprocessor 44 used in this embodiment is the Z8002, and the assembler used to generate this listing was the Z8002 assembler for the HP64000 computer. The assembly language program is stored in ROM 66 in the actual apparatus 20.

Although a number of embodiments of the invention have been particularly shown and described, it is to be understood by those skilled in the art that modifications in form and detail may be made therein without departing from the spirit and scope of the invention.

What is claimed is:

1. An apparatus for locating a dart embedded in a dart board comprising:
  - a housing for supporting the dart board;
  - means within said housing for illuminating a space adjacent a surface of the dart board supported within said housing;
  - means within said housing for detecting the presence of at least two shadows created by the presence of the dart within said illuminated space when said dart is embedded in said surface of the dart board supported within said housing;

60

65

means for utilizing the location of said shadows created by the presence of said dart within said illuminated space to calculate the location of said dart embedded in said dart board;

said means within said housing for detecting the presence of at least two shadows comprising a plurality of light detecting elements for monitoring the intensity of the illumination within said illuminated space, said plurality of light detecting elements being located along a side of said dart board opposite from said means within said housing for illuminating said illuminated space; and

each of said plurality of light detecting elements being capable of detecting a reduced level of illumination incident on said light detecting element when said light detecting element is within a shadow created by the presence of said dart within said illuminated space adjacent said surface of said dart board. 5

2. An apparatus as claimed in claim 1 wherein said means for utilizing the detection of said shadows created by the presence of said dart within said illuminated space adjacent to a surface of said dart board to calculate the location of said dart embedded in said dart board comprises: 10

a microprocessor responsive to a set of machine instructions for calculating the location of said dart embedded in said dart board, said set of machine instructions utilizing as input the output of said plurality of light detecting elements; and 15
electronic circuitry associated with said microprocessor for transmitting the output of each of said plurality of light detecting elements to said microprocessor to enable said microprocessor to identify which light detecting elements of said plurality of light detecting elements are detecting a reduced level of illumination indicative of the presence of a 25 shadow on that particular light detecting element.

3. An apparatus for locating a dart embedded in a dart board comprising:

a housing for enclosing a dart board; 30
first means within said housing for illuminating a space adjacent to a surface of a dart board enclosed within said housing; second means within said housing for illuminating said space adjacent to a surface of a dart board enclosed within said housing; 35
a first plurality of light detecting elements within said housing for monitoring the intensity of the illumination within said illuminated space adjacent to a surface of a dart board enclosed within said housing, said first plurality of light detecting elements 40 being located on a side of said dart board and oppositely located from said first means within said housing for illuminating said space adjacent to a surface of said dart board, each of said first plurality of light detecting elements being capable of detecting a reduced level of illumination on said light detecting element when said light detecting element is within a shadow created by the presence of a dart within said illuminated space adjacent to a 45 surface of said dart board when said dart is embedded in said surface of said dart board;

a second plurality of light detecting elements within said housing for monitoring the intensity of the illumination within said illuminated space adjacent to a surface of a dart board enclosed within said housing, said second plurality of light detecting elements being located on a side of said dart board oppositely located from said second means within said housing for illuminating said space adjacent to the surface of said dart board, each of said second 60 plurality of light detecting elements being capable of detecting a reduced level of illumination on said light detecting element when said light detecting element is within a shadow created by the presence of a dart within said illuminated space adjacent to a 65 surface of said dart board;

means for utilizing the detection of a shadow on said first plurality of light detecting elements and the

detection of a shadow on said second plurality of light detecting element created by the presence of a dart within said illuminated space adjacent to a surface of said dart board when said dart is embedded in said surface of said dart board to calculate the location of said dart embedded in said dart board;

said means for utilizing the detection of a shadow on said first plurality of light detecting elements and the detection of a shadow on said second plurality of light detecting elements to calculate the location of said dart embedded in said dart board comprising a microprocessor responsive to a set of machine instructions for calculating the location of said dart embedded in said dart board, said set of machine instructions utilizing as input the output of said first plurality of light detecting elements and the output of said second plurality of light detecting elements; and

electronic circuitry associated with said microprocessor for transmitting the output of each of said first plurality of light detecting elements to said microprocessor and for transmitting the output of each of said second plurality of light detecting elements to said microprocessor to enable said microprocessor to identify which light detecting elements of said first plurality of light detecting elements and which light detecting elements of said second plurality of light detecting elements are detecting a reduced level of illumination indicative of the presence of a shadow on that particular light detecting element.

4. An apparatus for locating a dart embedded in a dart board comprising:

a housing for enclosing a dart board; first means within said housing for illuminating a space adjacent to a surface of a dart board enclosed within said housing;

second means within said housing for illuminating said space adjacent to a surface of a dart board enclosed within said housing;

third means within said housing for illuminating said space adjacent to a surface of a dart board enclosed within said housing;

a first plurality of light detecting elements within said housing for monitoring the intensity of the illumination within said illuminated space adjacent to a surface of a dart board enclosed within said housing, said first plurality of light detecting elements being located on a side of said dart board and oppositely located from said first means within said housing for illuminating said space adjacent to a surface of said dart board, each of said first plurality of light detecting elements being capable of detecting a reduced level of illumination on said light detecting elements when said light detecting element is within a shadow created by the presence of a dart within said illuminated space adjacent to a surface of said dart board when said dart is embedded in said surface of said dart board;

a second plurality of light detecting elements within said housing for monitoring the intensity of the illumination with said illuminated space adjacent to a surface of a dart board enclosed within said housing, said second plurality of light detecting elements being located on a side of said dart board and oppositely located from said second means within said housing for illuminating said space adjacent to a surface of said dart board, each of said second

plurality of light detecting elements being capable of detecting a reduced level of illumination on said light detecting elements when said light detecting element is within a shadow created by the presence of a dart within said illuminated space adjacent to a surface of said dart board;

a third plurality of light detecting elements within said housing for monitoring the intensity of the illumination within said illuminated space adjacent to a surface of a dart board enclosed within said housing, said third plurality of light detecting elements being located on a side of said dart board and oppositely located from said third means within said housing for illuminating said space adjacent to a surface of said dart board, each of said third plurality of light detecting elements being capable of detecting a reduced level of illumination on said light detecting elements when said light detecting element is within a shadow created by the presence of a dart within said illuminated space adjacent to a surface of said dart board;

means for utilizing the detection of a shadow on said first plurality of light detecting elements and the detection of a shadow on said second plurality of light detecting elements and the detection of a shadow on said third plurality of light detecting elements created by the presence of a dart within said illuminated space adjacent to a surface of said dart board when said dart is embedded in said surface of said dart board to calculate the location of said dart embedded in said dart board;

said means for utilizing the detection of a shadow on said first plurality of light detecting elements and the detection of a shadow on said second plurality of light detecting elements and the detection of a shadow on said third plurality of light detecting elements to calculate the location of a dart embedded in said dart board comprising a microprocessor responsive to a set of machine instructions for calculating the location of said dart embedded in said dart board, said set of machine instructions utilizing as input the output of said first plurality of light detecting elements and the output of said second plurality of light detecting elements and the output of said third plurality of light detecting elements; and

electronic circuitry associated with said microprocessor for transmitting the output of each of said first plurality of light detecting elements to said microprocessor and for transmitting the output of each of said second plurality of light detecting elements to said microprocessor and for transmitting the output of each of said third plurality of light detecting elements to said microprocessor to enable said microprocessor to identify which light detecting elements of said first plurality of light detecting elements and which light detecting elements of said second plurality of light detecting elements and which light detecting elements of said third plurality of light detecting elements are detecting a reduced level of illumination indicative of the presence of a shadow on that particular light detecting element.

5. An apparatus for automatically scoring a dart game comprising:

a housing for enclosing a dart board adapted to receive darts therein;

a pair of light source within said housing for illuminating a space adjacent to the outer surface of the dart board;

a plurality of photoelectric cells arranged within said housing along a side of said dart board opposite said light sources for detecting the presence of at least two shadows created by the presence of a dart within said illuminated space adjacent to the outer surface of the dart board when said dart is embedded in said surface of the dart board enclosed within said housing, each of said shadows extending across more than one photoelectric cell;

electronic means responsive to the light intensity of said photoelectric cells created by the presence of said dart within said illuminated space adjacent to the outer surface of said dart board to calculate the location of said dart embedded in said dart board; and

means for automatically calculating the score of said dart embedded in said surface of said dart board from the location of said dart therein.

6. An apparatus as claimed in claim 5 wherein said means for automatically calculating the score of said dart embedded in said dart board comprising a microprocessor responsive to a set of machine instructions for calculating the score of said dart embedded in said dart board, said set of machine instructions utilizing as input the location of said dart embedded in said dart board.

7. A method for locating a dart embedded in a circular dart board comprising the steps of:

illuminating a space closely adjacent to the outer surface of the dart board in which the dart is embedded with at least two spaced light sources along a side of the dart board;

monitoring the intensity of the illumination within said illuminated space with a plurality of light detecting elements located along a side of said circular dart board opposed from the light sources;

detecting a reduced level of illumination incident on at least one light detecting element of said plurality of light detecting elements when said light detecting element is within a shadow created by the presence of said dart within said illuminated space; and

calculating the location of said dart embedded in said dart board from the detection of said shadows created by the presence of said dart within said illuminated space adjacent to the surface of said dart board.

8. A method as claimed in claim 7 where the step of calculating the location of said dart embedded in said dart board from the detection of said shadows created by the presence of said dart within said illuminated space adjacent to the surface of said dart board comprises the steps of:

transmitting the output of each of said plurality of light detecting elements to a microprocessor;

identifying by said microprocessor which light detecting elements of said plurality of light detecting elements are detecting a reduced level of illumination indicative of the presence of a shadow on that particular light detecting element; and

calculating by said microprocessor the location of said dart embedded in said dart board from the shadow location information.

9. A method for locating a dart embedded in a dart board comprising the steps of:

illuminating a space closely adjacent to the outer surface of the dart board in which the dart is embedded with a first illuminating means; monitoring the intensity of the illumination from said first illumination means within said illuminated space with a first plurality of light detecting elements located along a first side of said dart board; detecting the presence of the center of at least one shadow on said first plurality of light detecting elements created by the presence of the dart within said illuminated space when said dart is embedded in said surface of said dart board, said shadow extending across more than one light detecting element; illuminating said space closely adjacent to the outer surface of the dart board in which the dart is embedded with a second illuminating means; monitoring the intensity of the illumination from said second illumination means with a second plurality of light detecting elements located along a second side of said dart board; detecting the presence of the center of at least one shadow on said second plurality of light detecting elements created by the presence of the dart within said illuminated space when said dart is embedded in said surface of said dart board, said shadow extending across more than one light detecting element; and calculating the location of said dart embedded in said dart board from the detection of a shadow on said first plurality of light detecting elements and from the detection of a shadow on said second plurality of light detecting elements created by the presence of a dart within said illuminated space closely adjacent to the outer surface of said dart board when said dart is embedded in said surface of said dart board.

10. A method as claimed in claim 9 where the step of calculating the location of said dart embedded in said dart board from the detection of a shadow on said first plurality of light detecting elements and from the detection of a shadow on said second plurality of light detecting elements created by the presence of a dart within said illuminated space adjacent to a surface of said dart board when said dart is embedded in said surface of said dart board comprises the steps of:

transmitting the output of each of said first plurality of light detecting elements to a microprocessor; transmitting the output of each of said second plurality of light detecting elements to said microprocessor; identifying by said microprocessor which light detecting elements of said first plurality of light detecting elements and which light detecting elements of said second plurality of light detecting elements are detecting a reduced level of illumination indicative of the presence of a shadow on those particular light detecting elements; and calculating by said microprocessor the location of said dart embedded in said dart board from the shadow location information.

11. A method for locating a dart embedded in a dart board comprising the steps of:

illuminating a space adjacent to the surface of the dart board in which the dart is embedded with a first illuminating means; monitoring the intensity of the illumination from said first illumination means within said illuminated

space with a first plurality of light detecting elements located along a first side of said dart board; detecting the presence of at least one shadow on said first plurality of light detecting elements created by the presence of the dart within said illuminated space when said dart is embedded in said surface of said dart board; illuminating said space adjacent to the surface of the dart board in which the dart is embedded with a second illuminating means; monitoring the intensity of the illumination from said second illumination means with a second plurality of light detecting elements located along a second side of said dart board; detecting the presence of at least one shadow on said second plurality of light detecting elements created by the presence of the dart within said illuminated space when said dart is embedded in said surface of said dart board; illuminating said space adjacent to the surfaces of the dart board in which the dart is embedded with a third illuminating means; monitoring the intensity of the illumination from said third illumination means with a third plurality of light detecting elements located along a third side of said dart board; detecting the presence of at least one shadow on said third plurality of light detecting elements created by the presence of the dart within said illuminated space when said dart is embedded in said surface of said dart board; and calculating the location of said dart embedded in said dart board from the detection of a shadow on said first plurality of light detecting elements and from the detection of a shadow on said second plurality of light detecting elements and from the detection of a shadow on said third plurality of light detecting elements created by the presence of a dart within said illuminated space adjacent to a surface of said dart board when said dart is embedded in said surface of said dart board.

12. A method as claimed in claim 11 where the step of calculating the location of said dart embedded in said dart board from the detection of a shadow on said first plurality of light detecting elements and from the detection of a shadow on said second plurality of light detecting elements and from the detection of a shadow on said third plurality of light detecting elements created by the presence of a dart within said illuminated space adjacent to a surface of said dart board when said dart is embedded in said surface of said dart board comprises the steps of:

transmitting the output of each of said first plurality of light detecting elements to a microprocessor; transmitting the output of each of said second plurality of light detecting elements to said microprocessor; transmitting the output of each of said third plurality of light detecting elements to said microprocessor; identifying by said microprocessor which light detecting elements of said first plurality of light detecting elements and which light detecting elements of said second plurality of light detecting elements and which light detecting elements of said third plurality of light detecting elements are detecting a reduced level of illumination indicative of the presence of a shadow on those particular light detecting elements; and

calculating by said microprocessor the location of said dart embedded in said dart board from the shadow location information.

13. An electronic dart game apparatus for locating a dart embedded in a dart board and displaying a score calculated from the location of the dart comprising:

a housing having a central opening therein;
a dart board mounted within said central opening and having an exposed outer surface to receive darts thrown at said dart board;

light source means within said housing adjacent one side of the dart board for illuminating a space adjacent the exposed outer surface of said dart board and directing a light across the outer surface of the dart board;

a plurality of light detecting elements within said housing adjacent an opposite side of said dart board for monitoring the intensity of the illumination from said light source means within said illuminated space adjacent said outer surface of said dart board and detecting the presence of at least two shadows created by the presence of a dart within said illuminated space when said dart is embedded in said dart board adjacent the outer surface thereof;

means responsive to said light detecting elements to calculate the location of said dart embedded in said dart board;

means to calculate automatically the score of said dart embedded in said dart board from the location of said embedded dart; and

means on said apparatus to display visually the score calculated by the calculating means.

14. An electronic dart game apparatus for locating a dart embedded in a dart board and displaying a score calculated from the location of the dart comprising:

a generally rectangular box-like housing having a central circular opening in an outer wall of said housing;

a circular dart board mounted within said circular opening inwardly of said outer wall to define a space between said wall and an exposed outer surface of the dart board, said exposed outer surface adapted to receive darts thrown at said dart board through said circular opening and embedded therein;

a pair of light sources spaced from each other about the periphery of the dart board for illuminating said space adjacent the exposed outer surface of said dart board and directing light across said exposed outer surface of the dart board;

a plurality of light detecting elements within said housing for each of the light sources and positioned adjacent the periphery of the dart board opposite the associated light source for receiving light from said associated light source directed across the outer surface of the dart board, said light detecting elements monitoring the intensity of the illumination from said light source means and detecting the presence of at least two shadows created by the presence of a dart within said illuminated space when said dart is embedded in said dart board adjacent the outer surface thereof;

a microprocessor responsive to said light detecting elements to calculate the location of said dart embedded in said dart board;

electronic circuitry associated with said microprocessor for transmitting the output of each of said plu-

rality of light detecting elements to said microprocessor to enable said microprocessor to identify which light detecting elements of said plurality of light detecting elements are detecting a reduced level of illumination indicating the presence of a shadow on that particular light detecting element; means associated with said circuitry to automatically calculate the score of said dart embedded in said dart board from the location of said embedded dart; and

means associated with said calculating means to display visually the score calculated by the calculating means.

15. An electric dart game apparatus as set forth in claim 14 wherein each of said light sources directs light in a fan-like beam across the surface of the dart board on its associated plurality of light detecting elements, the associated plurality of light detecting elements being arranged generally in a row of continuous adjacent light detecting elements extending along a portion of the periphery of the dart board.

16. An electronic dart board apparatus as set forth in claim 14 wherein said light detecting elements are photoelectric cells.

17. An electronic dart board apparatus as set forth in claim 14 wherein said display means comprises a cathode ray tube screen.

18. An electronic dart game apparatus for locating a dart embedded in a circular dart board and displaying a score calculated from the location of the dart comprising:

a housing having a generally circular central opening therein;

a circular dart board mounted within said circular opening and having an exposed outer surface inset inwardly from the adjacent outer surface of the housing to form a space between the outer surface of the housing and the outer surface of the dart board through which darts are thrown at said dart board;

a pair of light sources spaced from each other about the periphery of the dart board and directing light beams across the outer surface of the dart board for illuminating said space;

a plurality of photoelectric cells for each of the light sources positioned in a continuous row adjacent the periphery of the dart board opposite the associated light source for receiving light from said associated light source directed across the outer surface of the dart board, said photoelectric cells monitoring the intensity of the illumination from said light source means and detecting the presence of at least two shadows created by the presence of a dart within said illuminated space when said dart is embedded in said dart board adjacent the outer surface thereof;

a microprocessor responsive to said photoelectric cells to calculate the location of said dart embedded in said dart board;

electronic circuitry associated with said microprocessor for transmitting the output of each of said plurality of photoelectric cells to said microprocessor to enable said microprocessor to identify which photoelectric cells of said plurality are detecting a reduced level of illumination indicating the presence of a shadow on that particular photoelectric cell;

means associated with said circuitry to automatically calculate the score of said dart embedded in said dart board from the location of said embedded dart; and

means associated with said calculating means to display visually the score calculated by the calculating means.

19. An electronic dart game as set forth in claim 18 wherein the shadow formed by a dart embedded in said dart board eclipses and extends across more than one photoelectric cell, and said microprocessor and associated circuitry determine the center of the shadow extending across a plurality of adjacent photoelectric cells.

20. An electronic system for locating the position of a dart embedded in a dart board for calculating the score obtained by such embedded dart, said system comprising:

a pair of light sources positioned adjacent said dart board at a known location and spaced from each other a known distance for directing light beams over the outer surface of the dart board in a closely spaced relation thereto along a generally vertical plane;

a plurality of adjacent light detecting elements for the light sources positioned in a generally continuous line along a generally vertical plane on a side of said dart board opposite the associated light sources for receiving light therefrom; and

30 electronic means including associated circuitry responsive to said light detecting elements for detecting the presence of at least two shadows created by the presence of an embedded dart extending through the light beams directed by said pair of spaced light sources, each of said shadows created by said dart extending across a plurality of light detecting sources, said electronic means and associated circuitry determining the center of the shadow extending across said plurality of light 35 detecting elements from the variation in light intensity from said associated light sources.

21. An electronic system as set forth in claim 20 wherein said electronic means and associated circuitry calculates the angle formed at each light source between a known line extending from the respective light source and a line extending from the respective light source to the embedded dart.

22. An electronic system as set forth in claim 21 wherein said electronic means and associated circuitry calculates the distance from each light source to the embedded dart thereby to calculate the score obtained by such embedded dart.

23. An electronic system for locating the position of a dart embedded in a dart board for calculating the score obtained by such embedded dart; said system comprising:

at least three light sources positioned at known locations about said dart for directing light beams in a generally vertical plane over the outer surface of the dart board closely spaced relation thereto;

a plurality of contiguous light detecting elements for the light sources positioned in a generally continuous line along a generally vertical plane on a side of the dart board opposite the associated light sources for receiving light therefrom directed across and in closely spaced relation to the outer surface of said dart board; and

electronic means including associated circuitry responsive to said light detecting elements for detecting the presence of at least three shadows created by the presence of an embedded dart adjacent the outer surface of the dart board extending through the light beams directed by said at least three light sources, said electronic means and associated circuitry determining the center of such shadows from the variation in light intensity from the associated light sources;

said electronic means and associated circuitry further calculating the distance from each light source to the embedded dart, and the angle between a known line extending from each light source and another line extending from the light source to the embedded dart thereby accurately locating the exact position of the dart for calculating the score therefrom.

24. A method of calibrating a microprocessor for locating a dart board accurately with respect to a housing on which the dart board is mounted for determining the accurate location of darts embedded in the dart board and the calculation of a score based on such location; said method comprising the steps of:

initially positioning the circular dart board in a centered position within a circular aperture in the housing;

positioned a pair of calibration pins at known locations on the dart board and at a known spacing between the pins;

positioning a pair of spaced light sources on the housing at known locations adjacent said dart board for directing light beams across the outer surface of the dart board, said light sources being spaced from each other a known distance;

positioning a plurality of light detecting elements on the housing adjacent said dart board for each light source on a side of said dart board opposite the associated light source for receiving light thereof, each of said plurality of light detecting elements being positioned in a generally continuous row facing the associated light source across the outer surface of the dart board, said calibration pins interrupting said light beams from said light sources and forming a shadow on the associated plurality of light detecting elements; and

providing a microprocessor and associated circuitry responsive to said light detecting elements to determine the angle formed at each light source between known lines extending from the associated light source and lines extending from the associated light source to the two calibration pins thereby to calibrate the microprocessor.

25. The method of calibrating a microprocessor as set forth in claim 24 further including the steps of:

positioning one calibration pin at the extent center of the dart board and positioning the other calibration pin at the bottom edge of the dart board; and positioning said pair of spaced light sources below said other pin along a common generally horizontal plane, said microprocessor and associated circuitry determining the vertical distance said other pin is positioned above said light sources.

26. A method of calibrating a microprocessor for locating the exact position of a dart board with respect to a support for the dart board thereby to permit the accurate location of darts embedded in the dart board for calculating a score based on such location; said

calibration method comprising the steps of:
 positioning the dart board at a generally centered position on the support;
 positioning a pair of calibration pins on the dart board at known locations on the dart board and at a 5 known spacing between the pins;
 positioning a pair of spaced light sources on the support at known locations adjacent said dart board for directing light beams across the outer surface of the dart board in closely spaced relation thereto, 10 said light sources being spaced from each other a known distance;
 positioning a plurality of contiguous light detecting elements for the light sources in a generally continuous row on a side of the dart board opposite the 15

light sources for receiving light therefrom directed across and in closely spaced relation to the outer surface of said dart board, said calibration pins extending through and interrupting said light beams and forming shadows on certain of the light detecting elements; and
 providing a microprocessor and associated circuitry responsive to said light detecting elements and the shadows formed by said calibration pins to determine the angle formed between lines extending from each light source to the pair of calibration pins thereby to calibrate the microprocessor for accurately locating the exact position of embedded darts to calculate the score therefrom.
